UNITED STATES PATENT OFFICE.

JAY A. FREIDAY, OF EAST ORANGE, NEW JERSEY, ASSIGNOR TO THOMAS E. MURRAY, OF BROOKLYN, NEW YORK.

FLUE EXPANSION JOINT.

Application filed June 1, 1927. Serial No. 195,673.

This invention relates to improvements in expansion joints for flues or conduits and the like and aims to provide means for preventing the accumulation of flue dust in such joints.

The invention will be apparent from the following specification when read in connection with the accompanying drawings in which—

10 Fig. 1 illustrates a boiler having a gas off-take flue provided with an expansion joint embodying my invention;

Fig. 2 is a longitudinal section on line 2—2 of Fig. 1;

15 Fig. 3 is a detail section on line 3—3 of Fig. 2;

Fig. 4 is a sectional perspective view illustrating structural details.

Referring to the drawings in detail, 10 is 20 a conventional boiler having a gas off-take flue or pipe 12 which is connected with a similar pipe 14 by my improved expansion joint indicated as a whole at 16. The pipe 14 in the installation shown connects with 25 an exhaust fan 18 which in turn connects with a stack or flue 20.

The expansion joint 16 includes a pair of oppositely disposed flexible plates 22, 24 which are secured to flanged annular rings 30 and 32 carried by the pipes 12 and 14 respectively. Secured to the outer portions of the plates 22 and 24 are the flanged angle-rings 30 and 32 which support an outer shell 34. This shell is of substantially cylindrical form, the ends of which terminate at 36 and 38. A removable section 40 abuts the ends 36 and 38 of the shell and is detachably secured in place by bolts 42 which pass through transverse angle bars 48 riveted at 46 to the ends of the arcuate plate or section 40, said bolts 42 passing through the flanges of the outer rings 30 and 32.

Expansion joints heretofore used have been rendered practically useless in a short time because they gradually fill up with soot or cinders and similar solids with the result that the flexible plates cannot move toward one another because of the mass of cinder or flue dust which accumulates between them. The removable section 40 permits ready removal of any accumulation between the plates and I also provide improved means for preventing accumulation of flue dust cinders and the like between the flex-

ible members of the joint. This means in 55 the embodiment illustrated comprises a sleeve-like bridge 50 which is suitably secured to the flue section 12, for example, by rivets 52 passing through the ring 26. The other end of the sleeve or bridge section 50 60 slidably engages the ring 28 carried by pipe or flue section 14 so as to permit a free movement to allow for expansion or slight movement relatively to the pipe 12. It is clear that the bridge or sleeve 50 will prevent dust 65 or other solids from dropping into the chamber 54 enclosed by the outer shell 34, thus the dust and cinders cannot accumulate and interfere with the relative movement of the flexible plates 22 and 24. 70

Various modifications may be made without departing from the invention as defined in the appended claims.

What I claim is:—

1. In combination with two spaced flue 75 sections forming an outlet duct for the products of combustion from a boiler furnace or the like, an expansion joint between said sections comprising a pair of oppositely disposed flexible plates secured to said sections, 80 flanged rims secured to said flexible plates, an outer shell secured to said rims and encircling the greater part thereof, a section detachably secured to said rims and closing the space not covered by said outer shell and 85 a bridge member fixedly secured to one flue section and having a clearance to permit relative movement of the other section.

2. In combination with two spaced flue sections forming an outlet duct for the products of combustion from a boiler furnace or the like, an expansion joint between said sections comprising a pair of oppositely disposed flexible plates secured to said sections, 90 flanged rims secured to said flexible plates, an outer shell secured to said rims and encircling the greater part thereof, a detachable section comprising a plate-like body portion adapted to abut the ends of said outer shell and thus close the space therebetween, said detachable section having transversely extending members overlapping the abutting joint between said shell and said plate-like body portion. 100

In witness whereof, I have hereunto 105 signed my name.

JAY A. FREIDAY.
